Primary Examiner — Leanne Was-Englehart(74) *Attorney, Agent, or Firm* — Rumit Ranjit Kanakia(57) **CLAIM**

The ornamental design for a scissor, as shown and described.

DESCRIPTION

FIG. 1 is a perspective view of a scissor showing my new design;
 FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view of area 9 encircled in FIG. 7.

The broken lines in the drawings represent the perimeter of the enlarged portion of the claimed design and does not form part of the claimed design.
